UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

HOPPER MECHANISM FOR AUTOMATIC FILLING-REPLENISHING LOOMS.

Application filed September 13, 1922. Serial No. 588,063.

To all whom it may concern:

Be it known that I, ALONZO E. RHOADES, a citizen of the United States, resident of Hopedale, county of Worcester, State of Massachusetts, have invented an Improvement in Hopper Mechanisms for Automatic Filling-Replenishing Looms, of which the following description, in connection with the accompanying drawing, is a specification, like characters on the drawing representing like parts.

This invention relates to automatic filling-replenishing looms in which a supply of filling carriers, such as bobbins, is maintained in a rotary hopper from which the filling carriers are successively transferred to the lay through the action of automatic mechanism. In the type of loom to which this invention relates, the rotatable hopper is provided with a ratchet wheel which is actuated by a feed pawl connected to or controlled in its movement by the transerrer which discharges the filling carriers from the hopper to the lay. This type of mechanism is characteristic of the well-known Northrop loom.

It is very important in this type of mechanism, that the hopper shall be rotated with precision so as to bring the fresh filling carriers successively into exactly the proper position for transfer; for, if the hopper is either rotated too much or too little to position the filling carrier to be transferred accurately the filling carrier will not be properly transferred and a smash is likely to result which will injure or break the filling carrier, the shuttle, or even the hopper stand of the loom.

The principal object of the present invention, therefore, is to provide a novel mechanism which will insure the proper and accurate presentation of the filling carriers in transferring position.

In hopper or battery mechanisms of this type, the feeding ratchet is usually cast integral with the hopper. Another object of the invention is to provide a ratchet disk which is adjustably secured to the hopper so that the relation of the teeth of the ratchet disk to the feeding pawl and to the locking dog may be so established that a more accurate positioning of the filling carriers may be effected and maintained.

A further feature of the invention is to provide a ratchet disk of this type with ac-

curately machined teeth adapted to cooperate with the feeding pawl and locking dog with greater accuracy than in previous constructions.

A further object of the invention is to provide detent mechanism for arresting the hopper as it is intermittently rotated in such positions that the filling carrier to be transferred will be properly located with respect to the shuttle.

A further object of the invention is to provide automatic means for releasing said detent mechanism during the movement of the transerrer to enable the hopper to be rotated to advance the next filling carrier in the hopper in transferring position.

These, and other objects and features of the invention, will more fully appear from the following description and the accompanying drawings, and will be particularly pointed out in the claims.

The invention is illustrated herein as applied to the hopper mechanism of the well-known Northrop type of loom.

In the drawings:

Fig. 1, is an end elevation partially in transverse section of a sufficient portion of the hopper mechanism of a loom to disclose the present invention in its preferred form embodied therein.

Fig. 2, is a plan view of the detent mechanism for arresting the rotation of the hopper and the means for actuating the same from the transerrer, a portion of the hopper stand being shown in cross section.

Fig. 3, is a vertical section through the lay and breast beam showing in elevation, the hopper stand, the detent mechanism, and the mechanism by which the same is operated from the transerrer.

Fig. 4, is a detail view in vertical section showing a portion of the hopper stand and throat and a portion of the hopper disk provided with a pivotal filling carrier support engaging the base of the filling carrier and detent mechanism in position to arrest the rotation of the hopper and,

Fig. 5, is a view similar to Fig. 4, showing the position of the pivotal filling carrier support and its relation to the detent mechanism when the filling carrier has been discharged.

The general construction of this type of loom being well-known and familiar to those skilled in the art, needs no extended de-

scription. Such a loom comprises the usual loom frame 1, breast beam 2, having a hopper stand 3 mounted thereon, and a lay 4, having at its end a shuttle box 5, to receive the shuttle 6. The hopper stand 3, has the usual circular hopper plate 7, provided with a stud 8, upon which the rotary hopper is mounted. The hopper comprises the usual hopper plate 9, having at its periphery a series of recesses 10, to receive the bases of the fresh filling carriers which are to be supplied to the shuttle.

One of the features of the present invention consists in providing novel yieldable supports for the bases of the filling carriers. The preferred form of support which is illustrated herein comprises a plate or lever 11, having a flat end portion adapted to engage the base of the filling carrier, said lever being mounted upon pintles 12, seated in suitable recesses or bearings in the hopper plate. The other end of the lever 11, is engaged by a spring 13, which tends to swing the filling carrier supporting lever about its pivot and to force the filling carrier engaging portion of the lever inwardly as illustrated in Fig. 5. When, however, the filling carrier is introduced, the filling carrier support is swung into substantially the vertical plane of the hopper plate as illustrated in Fig. 4, it being understood that the opposite end of the filling carrier is seated in a socket in a suitable support at the other end of the hopper as is usual in hopper construction of this character.

Each filling carrier support is provided with a stop member preferably in the form of a lug 14, which extends from the opposite face of the filling carrier supporting portion of the lever 11. A cooperating detent is provided to engage the stop members of the filling carrier support and arrest the rotation of the hopper when the foremost filling carrier has reached transferring position. The cooperating stop and detent therefore prevent any overthrow of the hopper, and in cooperation with the locking dog hereinafter described, accurately locate the filling carrier to be transferred in transferring position.

The preferred form of detent illustrated herein comprises a pin or locking bolt 15, which is reciprocably mounted in a suitable bearing 16, in the hopper stand, (see Fig. 2). The pin 17, or shoulder, upon the detent 15, serves to limit the inward movement thereof so that it will properly engage only the stop members 14 of the filling carrier supports. Any suitable mechanism may be provided for withdrawing the detent 15, from the path of the stop members 14 on the filling carrier supports in synchronism with the movement of the transferrer in order to enable the successive filling carriers to be presented in transferring position. As illustrated here-

in, the detent 15, is pivotally connected to a stud 18, in the end of a lever 19, which is pivotally mounted upon a stud 20, carried by a lug or bracket 21, on the hopper stand. A helical spring 22, having one end engaging the lever 19, and the other end seated upon a shoulder upon the lug or bracket 21, tends normally to force the end of the detent into the path of the stop members upon the filling carriers. 70 75

The lever 19, is provided with an upwardly extending end or arm 23, having a bevelled or cam faced upper end portion 24, positioned in the path of, and adapted to be engaged by a complementary bevelled face 80 or cam 25, upon the end of an arm 26, the opposite end of which is offset and connected by a machine screw 27, to the hub 28 of the transferrer.

The transferrer may be of the usual type comprising a hub 28 rotatably mounted upon a transfer stud 29, projecting from the hopper stand and having an arm 30, provided with a head 30^x to engage the positioned filling carrier and force the same into the shuttle. The transfer arm is normally maintained in uplifted position by a spring 31, wound upon and secured to the transferrer stud, and having one end extending under the transferrer arm 30. The transferrer is also provided with the usual downwardly extended arm 32, having pivotally mounted thereon a dog 33, which is moved by the usual controller mechanism, upon call for transferrer, into the path of the bunter 34, 100 upon the lay. The relative position of the arm 26, and its cam faced end 25, to the cam on the upwardly extending end portion 23 of the lever 19 is such that the lever 19, is actuated to withdraw the detent 15, from the path of the stop members 14, during the initial portion of the transferring movement of the transferrer and to withhold the detent from such position until after the filling carrier has been thrust from the filling carrier support 11, by the action of the transferrer so that the hopper may be rotated to advance the next succeeding filling carrier to transferring position. 105 110

Any suitable mechanism may be employed 115 for rotating the hopper intermittently to advance the successive filling carriers to transferring position. As illustrated herein, the hopper is rotated by a feed pawl 35, of the usual type, which is mounted upon the transferrer, said feed pawl being provided with a stud 36, which is journalled in a boss 37, on the transferrer arm 30. The feed pawl is provided with a laterally extending tooth 38, which is positioned to engage the teeth 39 of a ratchet disk 40, which is connected to the hopper. The backward rotation of the hopper is prevented by a locking dog 41, which is pivotally mounted upon a stud 42 on the hopper stand, the upper end 120 125 130 135 140

of the locking dog 41, being held in engagement with the teeth 39 of the ratchet disk by a suitable counter-weight 43. The locking dog is provided with a laterally extended arm, which projects over the hub of the transerrer in such position as to limit the swinging movement of the locking dog as it passes over the ratchet teeth during the rotation of the hopper and thereby insures proper engagement of said dog with the successive teeth of the hopper disk.

In previous construction the ratchet disk has been cast integral with the hopper plate. One of the important features of the present invention consists in providing a ratchet plate which is constructed independently of the hopper disk, and preferably provided with accurately machined teeth to cooperate with the tooth 38 of the feeding pawl 35, and with the locking dog 41, this ratchet disk being adjustably secured to the hopper plate at a remote distance from the stud about which the hopper rotates in order that an accurate relation may be established between the teeth of the ratchet plate, the feeding pawl and the locking dog. Preferably such adjustability is secured by attaching the ratchet disk 40 to the hopper plate 9, by bolts 44, extending through slots 45 in the ratchet disk and tapped into the hopper plate 9.

By reason of the construction above described, the action of the detent 15, in engaging the successive stop members 14, upon the filling carrier supports limits the rotation or feeding movement of the hopper while the accurately positioned teeth 39 of the ratchet disk 40, with relation to the locking dog 41, serves to lock the hopper positively upon each feeding movement in such position that the foremost filling carrier of the series carried by the hopper is presented in proper relation to the transerrer and shuttle and all danger of a smash or other improper transfer of the filling carrier is avoided.

The detent mechanism heretofore described, may be positioned to engage the stop member of any suitable filling carrier support. In the preferred construction illustrated herein, the detent is so positioned as to engage the stop of the next filling carrier support beyond the foremost filling carrier which is to be transferred, so that any possible interference of the detent mechanism with the transfer of the positioned filling carrier will be avoided.

Any suitable means may be provided for preventing the filling carrier which is positioned for transfer from dropping out or being dislodged from the filling carrier support. The present construction, however, is particularly adapted to the employment of a retaining finger for such purpose of the character illustrated in my prior Patent

#1,341,999 granted June 1, 1920, in which the hopper stand is provided with a channel shaped portion 46, in which a finger 47, is pivotally mounted upon a stud 48, seated in the walls of the channel shaped portion 46. The lower end of the finger 47, is bent laterally to extend beneath the base of the positioned filling carrier and is normally held in such position by a helical spring 49, which is seated in a suitable recess 50, in the channel shaped portion of the hopper stand and abuts against the back of the finger 47. The end portion of the finger 47, is provided with a bevelled surface 51, which is adapted to be engaged by the base of the filling carrier as it is being transferred and to swing the finger outwardly to permit the filling carrier to be transferred to the shuttle. An adjustable stop consisting of a bolt 52, which is secured in the hopper stand passes through a recess in the upper portion of the finger 47, and is provided with a head to engage said finger so that the bevelled end portion 51 of said finger may be properly positioned in relation to the filling carrier which is positioned for transfer.

It will be understood that the embodiment of the invention disclosed herein is of an illustrative character and is not restrictive and that various changes in form construction and arrangement of parts may be made within the spirit and scope of the following claims.

Having thus described my invention, what I claim as new, and desire to secure by Letters Patent, is:

1. In a filling replenishing loom comprising a rotatable hopper having a peripheral series of spring actuated supports to engage the bases of filling carriers, a transerrer and means for rotating said hopper intermittently after each transfer to present the filling carriers successively in transferring position; a stop member on each filling carrier support, a cooperating detent positioned to engage one of the filling carrier support stop members to arrest the rotation of the hopper with the foremost filling carrier positioned accurately for transfer, and means operable in synchronism with the movement of the transerrer to withdraw said detent from engagement with said stop member, to permit feeding movement of said hopper after transfer.

2. In a filling replenishing loom comprising a rotatable hopper having a peripheral series of spring actuated supports to engage the bases of filling carriers, a transerrer and means for rotating said hopper intermittently after each transfer to present the filling carriers successively in transferring position; a stop member on each filling carrier support, a cooperating detent positioned to engage one of the filling carrier support stop members

to arrest the rotation of the hopper with the foremost filling carrier positioned accurately for transfer, and means operable by the transferrer during its transferring movement to withdraw and withhold said detent from engagement with said stop member during the initial portion of the rotation of said hopper after transfer, and means for restoring said detent to operative position to engage the succeeding stop member before the completion of the intermittent rotative movement of said hopper.

3. In a filling replenishing loom comprising a hopper stand, a rotatable hopper having a peripheral series of spring actuated supports to engage the bases of filling carriers, a transferrer and means operable thereby to rotate said hopper intermittently after each transfer to present the filling carriers successively in transferring position; a stop member on each filling carrier support, a cooperating spring actuated detent mounted on said hopper stand and positioned to engage a stop member of one of the filling carrier supports and thereby arrest the rotation of said hopper with the foremost filling carrier positioned accurately for transfer, and means operable by said transferrer during its transferring movement to withdraw and withhold said spring actuated detent from engagement with said stop member during the initial portion of the rotative movement of said hopper.

4. In a filling replenishing loom comprising a hopper stand, a rotatable hopper having a peripheral series of spring actuated supports to engage the bases of filling carriers, a transferrer and means operable thereby for rotating said hopper intermittently after each transfer to present the filling carriers successively in transferring position; a stop member on each filling carrier support, a cooperating detent reciprocably mounted on said hopper stand and positioned to engage one of the filling carrier support stop members to arrest the rotation of the hopper with the foremost filling carrier positioned accurately for transfer, and means operable by the movement of the transferrer to withdraw said detent from engagement with said stop member, comprising an arm connected to said transferrer provided with a cam and a lever connected to said reciprocable detent positioned to be engaged by said cam during the movement of said transfer, and means to restore said detent to operative position to engage the stop member of the next succeeding filling carrier support.

5. In an automatic filling replenishing loom comprising a hopper stand, a rotatable hopper having a peripheral series of spring actuated filling carrier supports, a transferrer, a pawl carried by said transferrer and a co-operating ratchet on said hopper

operable by the movement of said transferrer to rotate said hopper intermittently; a stop member on each filling carrier support, a co-operating detent reciprocably mounted on said hopper stand, an arm connected to said transferrer provided with a cam and a lever connected to said detent adapted to be engaged by the cam upon said transferrer and operable thereby to withdraw said detent from the path of said stop members in advance of the actuation of said hopper by said transferrer pawl, and means to restore said detent to operative position in advance of the completion of the hopper rotating movement whereby the next succeeding stop member will be engaged by said detent.

6. In an automatic filling replenishing loom comprising a hopper stand, a detent reciprocably mounted thereon, a rotatable hopper, a transferrer, means operable thereby to rotate said hopper intermittently, a peripheral series of supports for the bases of filling carriers yieldably mounted on said hopper and adapted to be pressed outwardly upon insertion of a filling carrier, a stop member on each filling carrier support adapted upon rotation of the hopper to be engaged by said detent when the filling carrier support is loaded with a filling carrier and to pass by said detent when the filling carrier is unloaded, means operable by said transferrer to withdraw said detent from the path of said stop members during the initial portion of the intermittent rotative movement of said hopper, and means for restoring said detent to stop engaging position during the final portion of the intermittent rotative movement of said hopper.

7. In an automatic filling replenishing loom comprising a hopper stand, a hopper rotatably mounted upon a stud on said hopper stand having a peripheral series of supports for the bases of the filling carriers, a toothed feeding ratchet, a transferrer, a pawl carried thereby engaging said ratchet and operable by the movement of said transferrer to rotate said hopper, co-operating stop members acting to limit the forward intermittent movements of the hopper to position the filling carrier accurately in transferring position, and a dog engaging the teeth of said ratchet positioned to prevent backward rotation of said hopper; means located at a remote distance from said stud for adjustably securing said toothed ratchet to said hopper whereby the teeth of said ratchet may be positioned so as to co-operate accurately with said dog to prevent backward rotation of the hopper when the filling carriers are successively positioned properly for transfer.

8. In an automatic filling replenishing loom comprising a hopper having a peripheral series of supports for the bases of the

- filling carriers, a feeding ratchet having machined teeth, a transferrer, a pawl carried thereby engaging said ratchet and operable by the movement of said transfferer to rotate said hopper, co-operating stop members acting upon the hopper adjacent to its periphery to limit the intermittent forward movement of the hopper to position the filling carrier accurately in transferring position, a dog having a machined tooth to engage the teeth of said ratchet positioned to prevent backward rotation of said hopper, means for adjustably securing said ratchet to said hopper whereby the teeth of said ratchet may be so positioned as to co-operate accurately with said dog to prevent backward rotation of the hopper when the filling carriers are successively positioned properly for transfer.
9. In an automatic filling replenishing loom comprising a hopper having a peripheral series of supports for the bases of the filling carriers, a toothed feeding ratchet, a transfferer, a pawl carried thereby engag-
- ing said ratchet and operable by the movement of said transfferer to rotate said hopper, and a dog engaging the teeth of said ratchet positioned to prevent backward rotation of said hopper; means for adjustably securing said toothed ratchet to said hopper whereby the teeth of said ratchet may be positioned so as to co-operate accurately with said dog to prevent backward rotation of the hopper when the filling carriers are successively positioned properly for transfer, and stop mechanism for positively arresting the forward rotation of said hopper when the foremost filling carrier reaches transferring position including a lug upon each filling carrier support and a co-operating detent mounted on the hopper stand and means operable in synchronism with the movement of the transfferer to withdraw said detent from engagement with said lug to permit feeding movement of the hopper after transfer.
- In testimony whereof, I have signed my name to this specification.

ALONZO E. RHOADES.
